Patented Aug. 23, 1927.

UNITED STATES PATENT OFFICE.

JOHN LEICHT, JR., OF BURLINGTON, IOWA.

BAG HOLDER.

Application filed February 27, 1926. Serial No. 91,059.

This invention has for its object the provision of a bag holder of novel construction which may be suspended over a store counter and carry a supply of bags of various sizes in such a manner that a bag of a desired size may be easily withdrawn. The invention also has for its object the provision of means whereby containers for bags of assorted sizes may be retained in an overhead rack or carrier but easily removed when necessary to be refilled, the containers being constructed to permit the removal of them singly, as needed, without disturbing the adjoining containers or the carrier. Other incidental objects will appear in the course of the following description.

In the accompanying drawings;

Figure 1 is a perspective view of a bag holder embodying my present invention;

Figure 2 is a vertical section through the length of a container;

Figure 3 is a bottom plan view of a container;

Figure 4 is a detail view showing partitions employed in a container;

Figure 5 shows another method of suspending the containers.

The complete apparatus embodying my invention includes a rack or frame and a plurality of containers supported by the rack or frame. In the form shown in Figs. 1 and 2, the frame or rack is of skeleton or open form and comprises rectangular end frames 1, preferably of angle bars, connected at their upper rear ends by a strip 2 whereby rigidity will be attained. The end frames are connected at their lower rear corners by a strip 3 of angle form whereby it is adapted to support the rear ends of the containers and prevent rearward endwise movement of the latter, while a similar but narrower strip 4 connects the lower front corners of the end frames and provides a restraining support for the front ends of the containers. A bar 5 connects the upper front corners of the end frames so that spreading of the end frames will be effectually prevented.

The rack is suspended from a ceiling or other fixed support by chains 6 or their equivalents attached to the end frames of the rack.

The bags are carried in a series of containers 7 graduated in size and each adapted to hold the bags of a given size. These containers have side and end walls but may

be open at the top to facilitate the placing of bags therein while their bottoms are each provided with a slot 8 to permit withdrawal of the bags. The containers are disposed side by side and rest at their ends upon the plates 3 and 4, the flanges of the plates preventing the containers from sliding out of the rack. The bags 9 are piled in the containers with the flaps 10, formed by folding their bottoms, overlying the slots 8, and when a bag is to be extracted the flap or fold 10 is grasped and drawn down through the adjacent slot 8.

It will be noted upon reference to Figs. 2 and 3, that the slot 8 is T-shaped, the stem of the T extending along the medial longitudinal line of the container and through the greater portion of the length of the container. As a result of this formation, a bag in the act of withdrawal moves forwardly and downwardly so that its removal is easily and smoothly accomplished, and the bottom bag is always readily accessible. The slot 8 is defined by and the bottom of the container consists of a front plate 11 which is secured rigidly to and between the sides of the container at the front end thereof, and a rear plate 12 which is in the form of a fork extending from the rear end of the container and presenting side rests 13, said rear plate being also rigidly secured to and between the sides of the container. Upon reference to Fig. 2, it will be noted that the plate 12 is thicker than the plate 11 so that its upper surface will be offset vertically relative to the latter plate. The body portions of the bags will thus be elevated somewhat above the flaps thereof so that the flaps will lie partly open and may be easily grasped, and, to avoid tearing of the bags, the edges over which they are drawn are convex, as shown at 14 and 15. When a bag is drawn downward, it collapses along its central line to pass through the outlet slot and this collapsing or partial folding of the bag overcomes any adhesion between it and the superposed bag.

In Fig. 5 I have shown a support 16 consisting of a single open frame, and the containers are equipped at their ends with standing hooks 17 to engage over the sides of the frame and suspend the containers therefrom.

Bags have not been standardized to such an extent that all bags of a given width

2
will be equal in length. It will, consequently, be necessary at times to place in a container bags which are shorter than the capacity of the container. To meet this condition and bring the folds of the bags over the slot 8, I provide partitions 18 which are inserted in the containers and held by being engaged at their edges in selected grooves 19 formed in the sides of the containers.

10 The sides of the rack or suspending frame lend themselves readily to advertising. Metallic plates 20 may be secured in any convenient manner to the bars of the rack and reentrant flanges 21, formed along the top and bottom edges of the plates, present grooves in which display cards may be removably engaged and held.

15 The device is very simple in construction and will maintain a large supply of bags within convenient reach of salesmen without curtailing the space desired for the display of goods or interfering with the move-

ments of clerks or customers. While the containers will be firmly held by the rack, 25 any container may be easily removed when necessary without disturbing any other container and the supply of bags may thus be easily replenished whenever necessary.

20 Having fully described my invention what I claim as new and desire to secure by Letters Patent, is:—

A bag holder comprising a container having ends and sides, a front bottom plate secured between its sides, and a rear bottom plate also secured between its sides, said rear plate having parallel side members terminating short of the front plate whereby a T-shaped slot is defined through the bottom of the container, the depth of the container 40 over the rear plate being less than its depth over the front plate.

25 In testimony whereof, I have signed this specification.

JOHN LEICHT, JR.
